FIG. 4.

UNITED STATES PATENT OFFICE

2,455,036

BRASSIÈRE

Gypsy A. Boylan, Rocky River, Ohio

Application March 22, 1946, Serial No. 656,271

3 Claims. (Cl. 2—42)

1

This invention relates to a woman's apparel, more particularly a brassière.

All apparel, commonly referred to as brassières, of which I have knowledge, usually consist of straps or ribbons so connected to the front portions or cups and each other that during bodily movements of the wearer certain of the straps are put under tension and hence cut into the shoulders of the wearer and/or bind her diaphragm and otherwise cause discomfort; other forms of the apparel include a body fitting portion extending around or above the wearer's waist, forming in effect a sort of stayless semi-corset. In these types of apparel, the straps or other portions of the apparel must be buckled or hooked together each time the apparel is donned. Also, aside from the undue amount of material employed, the added weight must be largely supported by the wearer's shoulders and the straps and other parts of the apparel must closely fit the wearer's body. Where the apparel closely fits the wearer's bust considerable discomfort results from bodily movement of the arms and/or shoulders on the part of the wearer.

One object of the invention is to provide an improved brassière wherein a minimum amount of material is required, and consisting of breast cups and supporting straps therefor connected to the cups and each other to permit freedom of bodily movement on the part of the wearer without discomfort, while maintaining a substantially uniform tension between all portions of the supporting straps and the wearer's body, whereby danger of the shoulder engaging portions of the straps cutting into the wearer's body is eliminated.

Another object of the invention is to provide an improved brassière wherein the supporting straps therefor have a floating relation, whereby unequal tension on the latter or portions thereof during bodily movement of the wearer is avoided, to insure the wearer's comfort and at the same time maintain the cups or bust members of the brassière in permanent position.

Another object of the invention is to provide a brassière of simple construction, the supporting straps of which are connected together to permit their automatic adjustment, one relative to the other, during bodily movement of the wearer, whereby stresses on the body of the wearer due to tension on either strap and displacement of either strap are eliminated.

Another object of the invention is to provide an improved brassière of simple construction having a pair of straps forming the sole support

2

for the bust members of the brassière and a floating connection between the straps, the connections of the straps with the bust members and with each other being related to prevent displacement of the float connection, whereby, during bodily movement of the wearer, the straps are maintained in normal position and a belt or connections with each other garments worn by the wearer are eliminated.

A further object of the invention is to provide an improved brassière having a pair of supporting straps forming the sole support for the breast members of the brassière and connected thereto and each other for adaptation to the backs of wearers of varying sizes, whereby economy in manufacture results and the distributor's need for carrying a stock of many different sizes of brassières is reduced.

Other objects of the invention will be apparent to those skilled in the art to which my invention relates from the following description taken in connection with the accompanying drawings, wherein

Fig. 1 is an elevation view of a brassière embodying my invention.

Fig. 2 is a perspective view showing the brassière in position on a wearer.

Fig. 3 is a rear view.

Fig. 4 is a view similar to Fig. 3 but showing the position of the supporting straps or ribbons during bodily movement of the wearer.

Fig. 5 is a fragmentary view showing the float connection between the supporting straps or ribbons, enlarged.

Fig. 6 is a fragmentary view showing the adjustable connection between one of the straps or ribbons with the extension on one of the bust members.

Fig. 7 is a fragmentary view showing a modified arrangement of the supporting straps.

Fig. 8 is an elevation view, corresponding to that of Fig. 1, but showing the Fig. 7 embodiment of the invention.

In the drawing, 1, 2, indicate the breast members or cups of suitable construction and formed of any desired material dependent on the use of the brassière, each member being provided with a reinforced side edge 1a. Each member 1, 2, may be round, but is shown as of approximate triangular shape having a base 1b and sides 1c, forming an apex 1d at their upper ends. The inner sides 1c of the members 1, 2, are connected together by a web 3. The outer side 1c of each cup 1, 2, preferably adjacent the base 1b, is provided with an extension 4, adapted to extend

around the side of the wearers body. 5, 6, indicate supporting straps or ribbons, the strap or ribbon 5 being connected to the apices 1d of the cups 1, 2, and its intermediate portions being arranged to extend over the shoulders of the wearer and the other strap or ribbon 6 being connected to the free ends of the extensions 4 and arranged to extend across the back of the wearer. Where the cup members 1, 2, are substantially round, the opposite ends of the strap are connected thereto centrally of their upper edges. As shown in Figs. 1, 3, 4, and 5, a floating connection is provided between the straps 5, 6, intermediate their opposite ends, which connection permits automatic adjustment of each strap relative to the other strap as a result of bodily movement of the wearer. The floating connection consists of a member 7 through which each strap 5, 6, is reeved and is adapted to freely slide endwise. The member 7 preferably consists of a ring the wall of which in cross section is rounded throughout its circumference. The strap 6 operates through the ring 7 to hold the back engaging portions of the strap 5 in position and as both straps 5, 6, freely slide endwise through the ring and the latter is free to move (being unattached to any garment of the wearer), both straps readily adjust themselves relative to each other and the body of the wearer due to pull or tension on either or both straps when bodily movement of the wearer takes place. Accordingly, substantially equal tension on both straps, between the apices 1d and extensions 4 is maintained at all times and danger of the ring being displaced into an inoperative position is eliminated. As the extensions 4 are relatively wide and lie flat against the wearer's body and these extensions and the straps are formed of fabric materials, the lateral portions of the strap 6 are capable of movement when put under tension, without affecting the position of the cup members 1, 2. It will be observed that the straps 5, 6, extend into and through the ring 7 from opposite sides thereof, so that the tension of the straps operates in opposite directions on the upper and lower portions of the ring 7 and hence the straps co-operate to maintain the ring in vertical position and flat against the wearer's back. Each strap 5, 6, consists of a long section fixed at its inner end to one of the cups, as already set forth, and a short section 8 fixed at its inner end to the free end of the adjacent extension 4, the free ends of the sections and extensions 4 being adjustably connected by a suitable buckle or other type of friction device 9, or hooks and eyes. It will be observed that the long and short sections of the straps 5, 6, may be formed entirely of elastic material, but by preference the short sections 8 and the end portions of straps which are fixed to the cups and the adjacent extension 4, are formed of elastic material, as shown at 8a.

Fig. 8 illustrates a modified form of construction consisting of cups 1', 2', having sides 1a', 1c', and a base 1b', and two straps 5', 6', the strap 5' being fixedly connected to the extension 4' on the cup 1' and adjustably connected to the elastic section 8' which is connected to the apex 1d' of the cup 2' and the strap 6' being fixedly connected to the apex 1d' of the cup 1' and adjustably connected to the elastic section 8' which is connected to the extension 4' on the cup 2'. The straps 5', 6', extend through and freely slide endwise in a ring 7' to permit their relative adjustment in the manner already set forth.

In use, the brassière is first applied to a wearer

and by means of the device 9, the sections of the straps 5, 6, are adjusted to fit the wearer. These sections of the straps 5, 6, remain connected and thereafter the brassière may be donned by positioning both straps over the wearer's head and projecting the wearer's arms between them, removal of the brassière being affected in the reverse direction. By employing two supporting straps only for the cups 1, 2, and providing an adjustable connection for each strap, a predetermined size of brassière may be worn by persons whose back widths vary in size, so that in manufacture a multitude of different sized brassières is not required.

15 While I have described the apparel as a brassière, it is obvious that it may be formed of suitable material and employed as a halter as part of a bathing suit.

To those skilled in the art to which my invention relates many changes in construction and widely differing embodiments of the invention will be apparent without departing from the spirit and scope thereof. My disclosures and the description herein are purely illustrative and are 20 not intended to be in any sense limiting.

What I claim is:

1. A garment of the class described comprising a pair of cup members connected together at their inner sides, strap members connected at their opposite ends to the top and outer side portions of said cup members, the end portions of the strap members adjacent to their connections to the top portions of the cup members being adapted to extend over the shoulders of a wearer for supporting the garment, and a connecting member through which the intermediate portions of said strap members extend, said connecting member having a single opening and being of circular shape and rounded throughout to permit said strap members to slide freely endwise through said connecting member independently of each other and equalize the tension on said strap members during bodily movement of the wearer.

45 2. A garment of the class described comprising a pair of cup members connected together at their inner sides, an upper strap member connected to the top portion of each cup member, a lower strap member connected to the outer side portion of each cup member, portions of the upper strap member on each side of its intermediate portion being adapted to extend over the shoulders of a wearer for supporting the garment, and a connecting member through which the intermediate portions of the strap members extend, said connecting member having a single opening and being of circular shape and rounded throughout to permit said strap members to slide freely endwise through said connecting member independently of each other and equalize the tension on said strap members during bodily movement of the wearer.

3. A garment of the class described comprising a pair of cup members connected together at their inner sides, a pair of strap members each connected to the top portion of one of the cup members and to the outer side portion of the other cup member, with portions of the strap members being adapted to extend over the shoulders of a wearer for supporting the garment and with the intermediate portions of the strap members crossing each other at a point below the level of said shoulders, and a connecting member through which said intermediate portions of the strap members extend, said connect-

ing member having a single opening and being of circular shape and rounded throughout to permit said strap members to slide freely end-wise through said connecting member independently of each other and equalize the tension on said strap members during bodily movement of the wearer.
